United States Patent Office

Des. 185,961

Patented Aug. 25, 1959

185,961

HOUSING OF A TELEPHONE

Haruo Nogami, Tokyo, Japan

Application March 17, 1958, Serial No. 50,047

Term of patent 3½ years

(Cl. D26—14)

Fig. 1 is a front perspective view of the housing of a telephone showing my new design;

Fig. 2 is a rear perspective view thereof;

Fig. 3 is a left front perspective view thereof;

Fig. 4 is a right rear perspective view thereof; and

Fig. 5 is a left end perspective view thereof.

I claim:

The ornamental design for a housing of a telephone, substantially as shown.
